UNITED STATES PATENT OFFICE.

JASPER C. OWENS, OF LOS ANGELES, CALIFORNIA.

KNIFE.

1,013,844.

Specification of Letters Patent.

Patented Jan. 2, 1912.

Application filed January 11, 1911, Serial No. 602,010. Renewed October 30, 1911. Serial No. 657,622.

To all whom it may concern:

Be it known that I, JASPER C. OWENS, a citizen of the United States, residing at Los Angeles, in the county of Los Angeles and State of California, have invented new and useful Improvements in Knives, of which the following is a specification.

This invention relates to a knife particularly adapted for the cutting of linoleum and like articles, the prime object being the provision of a strongly constructed knife in a shape adapted for this class of work and with a detachable blade. The parts of the knife are so arranged that the sheath surrounding the blade forms a heavy reinforcement for the same, the blade consequently being comparatively thin and light and capable of receiving and keeping a fine edge. If a blade is broken it is only necessary to procure a new blade instead of procuring a whole new knife as formerly. By reason of making the blade thin and containing little metal it is possible to put into its manufacture a much higher grade of steel than is ordinarily used, and still keep the cost of the knife at a reasonable figure. Moreover, the sheath is made of a material, such as mild steel, which is not so brittle as the knife steel, being consequently much less liable to breakage and protecting the knife blade from injury.

Another feature of my device is the provision of a double ended knife, the blade being reversed in the sheath when one edge has been dulled.

In the accompanying drawings I have shown the forms preferably taken by my invention for the purpose of cutting linoleum. Minor changes may adapt it to other uses.

In the drawings: Figure 1 is a side elevation of the preferred form of my invention. Fig. 2 is a plan of the same. Fig. 3 is a side elevation of the knife blade. Fig. 4 is an enlarged section taken on line 4-4 of Fig. 1. Fig. 5 is an enlarged section taken on line 5-5 of Fig. 1. Fig. 6 is a side elevation of a modified form. Fig. 7 is an enlarged section of a modified form.

In the drawings 5 designates a handle to which is rigidly affixed the sheath. Sheath 6 in the preferred form is of circular side configuration, being completely closed on its end near the handle 5 and open on its other end. The back portion 7 of the sheath is enlarged in the form of a rib to inclose the

bead 8 on the back of knife 9. Portion 7 of the sheath extends down over the beaded back of the knife to a point close to the cutting end of the knife blade, while the inner portions of the sheath are cut away as at 10 to expose the cutting edge of the knife blade back to a point near the middle of the blade. The edges of the sheath at 10 are beveled away, as is best shown in Fig. 4 so as to present no edges which might catch on the article being cut.

In Fig. 1 the sheath is shown with its curved portions truly circular, the back of the knife also being circular. The body of the knife blade can consequently be of uniform width and still slip easily into the sheath, its end resting against the closed end of the sheath as is shown in Fig. 1. A small set screw 11 bears against the knife blade and prevents it moving out of the sheath.

In Fig. 6 I have shown a modified form in which the sheath and blade are curved in some manner other than on the circumference of a circle, preferably on a curve flattening at the end and curving greatest in the center. In such a case it is necessary that the sheath and blade shall taper from the center toward both ends in order that the blade shall be introduced to the sheath and fit snugly therein. Otherwise, the structure of the knife is practically the same as above described.

In Fig. 7 I have shown a section of a knife of modified form in which the bead is omitted. This form may be used as well as the preferred form.

Having described my invention, I claim:

1. A knife, comprising a handle, a thin sheath of curved configuration mounted upon the handle and closed at its end nearest the handle and open at its other end and along its inner edge near the open end, a cutting blade of similar curved configuration and having cutting edges on its inner edge near its ends, the blade being adapted to fit within the sheath with one end projecting from the open end thereof and its cutting edge projecting from the open inner edge of the sheath, and means to hold the blade in place in the sheath.

2. A knife, comprising a hollow sheath of curved configuration, being entirely closed at one end and being open at its other end and along its inner edge adjacent the open end, and a knife blade of similar curved con-

figuration sharpened on its inner edge and
adapted to be slipped longitudinally into the
sheath, leaving one end projecting from the
open end thereof and its sharpened edge
5 projecting from the open inner edge of the
sheath.

In witness that I claim the foregoing I

have hereunto subscribed my name this 3rd
day of January 1911.

JASPER C. OWENS.
